UNITED STATES PATENT OFFICE.

CHARLES BEMIS REARICK, OF NEW YORK, N. Y., ASSIGNOR TO CONNECTICUT TURBINE MANUFACTURING COMPANY, OF NEW LONDON, CONNECTICUT, A CORPORATION OF CONNECTICUT.

STEAM-TURBINE.

1,084,031.

Specification of Letters Patent.

Patented Jan. 13, 1914.

Application filed February 20, 1912. Serial No. 678,828.

To all whom it may concern:

Be it known that I, CHARLES BEMIS REARICK, a citizen of the United States, and resident of the city, county, and State of New York, have made a certain new and useful Invention Relating to Steam-Turbines, of which the following is a specification, taken in connection with the accompanying drawings, which form part of the same.

In the accompanying drawings showing illustrative embodiments of this invention in a somewhat diagrammatic way, Figure 1 is a longitudinal section through a turbine, parts being broken away. Fig. 2 is a transverse partial section along the line 2—2 of Fig. 1. Fig. 3 is a longitudinal sectional view showing a detail of a modified admission device. Fig. 4 is an enlarged sectional view corresponding to Fig. 1. Fig. 5 is a detail showing another retainer rod mounting. Fig. 6 is a similar detail showing still another retainer mounting for a nozzle member. Fig. 7 is an enlarged transverse section taken substantially along the line 7—7 of Fig. 4. Fig. 8 is a detail sectional view through the wheel bucket and return passage taken substantially along the line 8—8 of Fig. 7. Fig. 9 is an enlarged sectional view showing the packing devices used in Fig. 1. Fig. 10 is a view of another packing ring; and Fig. 11 is a sectional view showing the same in position.

In the illustrative form of turbine shown somewhat diagrammatically in Figs. 1 and 2, the casing of the turbine may be formed as by casting in several longitudinal sections each provided with suitable partitions such as 16 to form wheel chambers within the casing and also being provided with securing flanges, such as 6, for connecting the casing sections firmly in relative position. The nozzles may be conveniently mounted in the casing in longitudinally alined nozzle apertures, such as 21, bored or otherwise formed therein and the casing is preferably provided with an integral annular admission passage, such as 8, which may coöperate with a high pressure wheel chamber of considerably larger diameter than some of the other lower pressure chambers. The nozzle members, such as 10, in this high pressure wheel chamber may be secured in position in nozzle apertures, such as 9, bored longitudinally through the projecting high pressure

chamber beyond the main body of the casing so as to allow the desired number of such nozzle members to be secured in these nozzle apertures. Instead of an integral admission passage to admit steam or other elastic fluid to the turbine a separate annular admission pipe, such as 13, may be used for this purpose and may have supply branches 14 connected by suitable flanges, such as 15, with connections to each of the nozzle members 10 in the high pressure chamber.

The bucketed wheel, such as 5, in the high pressure chamber may have considerably larger diameter than the wheels 4 in one or more of the other lower pressure chambers of the turbine so that this high pressure wheel because of its larger diameter can have a correspondingly greater peripheral speed which is desirable in operating most efficiently with the high pressure steam with which it is supplied. This turbine wheel 5 of any desired construction may be rigidly mounted in any desired way on a shaft, such as 1, running in suitable bearings in the casing and this shaft may also carry other wheels, such as 4, in the other wheel chambers, the lower pressure chambers having if desired several wheels in each chamber so as to handle more efficiently the larger volume of steam. These turbine wheels may each be formed with an annular series of lapped buckets arranged in any desired way adjacent their periphery as by forming the buckets in the flat side or in the circumferential portion of the wheel and if desired the buckets 81 may be in the circumferential part of the wheel and located between integral partitions cast with the wheel rim itself. The entire wheel may be formed of cast material provided with an integral hub coöperating with the shaft as in the case of the wheel 4 shown in Fig. 1 and the high pressure wheel 5 may be similarly formed as indicated in Fig. 3. If desired, however, one or more of the wheels may be formed with a cast rim provided with integral bucket partitions and this rim may be formed with a suitable rim flange 19 as shown in Figs. 1 and 4 with which separate web plates, such as 17, may coöperate and be firmly held in position as by the series of rivets or bolts 18. These web plates may be firmly secured to the wheel hub of any desired construction as by forming these web plates with outwardly projecting reinforce-

ing hub flanges or alining collars 70 engag-
ing the hub 71 and held in alinement there-
with while rivets or bolts, such as 18, may
firmly secure these web plates to the project-
ing flange 69 on the hub.

In order to detect and control any possible
leakage between the wheel chambers, it is de-
sirable to form suitable telltale passages in
the partitions, so that in the event of leak-
age of motive fluid across such partitions the
steam or the like would issue from such tell-
tale passages and call attention to such leak-
age so that repairs may be made. Suitable
substantially radial telltale passages, such
as 7, may be formed in the partitions 16 as
indicated in Figs. 1 and 2, these telltale pas-
sages being preferably alined in the meeting
edges of the coöperating casing partitions,
and if desired a transverse telltale hole, such
as 97, may be made in the casing flange 6 so
as to communicate with both of these tell-
tale passages and also penetrate the packing
12 of any desired description which may be
used between the casing sections. For some
purposes it is desirable to have a suitable
telltale valve 96 to control the discharge of
fluid from the telltale hole 97 so that this
valve may be opened when desired to test
for leakage into the corresponding telltale
30 passages. Similarly alined curved telltale
passages 7 may be formed around the inner
surface of the admission passage 8, for ex-
ample, and in other parts of the casing
partitions or meeting edges where leak-
age is possible. A desirable form of shaft
packing for use in this connection is shown
in Figs. 1 and 9. The casing partitions
16 may be formed in any desired way as
when originally casting them with suit-
able dovetail recesses to accommodate the
dovetail projections 68 on the packing hous-
ing or socket 2 which may be machined to
the desired size and divided into sections
which may be accurately positioned with re-
spect to the casing by bringing their circum-
ferential portions into contact with the axial
bore through the casing partitions. The
packing housings may be readily secured in
position by casting into the dovetail recesses
50 suitable Babbitt or other fusible metal which
firmly holds the parts in position. If de-
sired, the shaft 1 may be provided with a
suitable bearing sleeve, such as 74, to coöper-
ate with the packing ring and this bearing
sleeve may be held in position between the
wheel hubs 72 by forming the calking
grooves 75 in the sleeve. Any suitable me-
tallic packing may be mounted within the
packing housing, the sectional packing ring
60 being illustrated as formed with a suit-
able butt lapped joint 73, the ring sections
being held in position in any desired way as
by the inclosing spring ring 80, which may
be snapped in place around the sections of
the packing ring. Another method of hold-

ing the packing in position is shown in Fig.
11 in which the bearing portion of the casing
partition 16 is shown as formed with a suit-
able recess which may be machined so as to
accommodate the packing housing 82 which
may be firmly secured therein by the calking
grooves 75. This packing housing may ac-
commodate a packing ring of any desired
construction and a suitable form of packing
ring for coöperation therewith may com-
prise a plurality of rings which may each be
turned up and then severed into the desired
number of ring sections or segments 77
formed with suitable sockets 79 at their
meeting ends into which are fitted pins 78
80 accurately filling the sockets and each hav-
ing a length equal to the thickness of the ad-
jacent ring sections to allow swiveling there-
of. Two such built-up rings may have their
socket pins 78 spaced apart as indicated in
Fig. 10 so as to make a substantially steam
tight packing ring which may be held in
place on the bearing sleeve by suitable
spring rings or coils, such as 80.

Suitable retainers for holding the nozzle
members and their connected supporting
nozzle tubes in position are shown in Fig.
4 in which the retainer member or rod 25
may have its end coöperate with a suitable
seat 23 in the nozzle member 10 and the
threaded end of this retainer rod may co-
operate with the threaded retainer spider or
crow foot 22 coöperating with the alined
nozzle aperture 21 in the casing partition
on the opposite side of the wheel chamber
without undesirably retarding the flow of
motive fluid through such nozzle aperture,
accurate alinement being secured if desired
by the use of suitable alining lugs 42 on the
spider. The parts may be properly assem-
bled by inserting through the nozzle aper-
ture a suitable wrench or other device to
engage and turn from outside the end of
the casing the square head 26 which may be
formed on the retainer rod and screw up this
rod so as to force the nozzle member 10
tightly into coöperation with the nozzle aper-
ture 21 in the opposite partition, in connec-
tion with which suitable packing may be
used if desired, the nozzle member being if
desired formed with a supporting nozzle tube
having a suitable flange 28 which may co-
operate with a suitable recess in the parti-
tion. When the retainer rod is tight enough
to hold the parts securely in position the
locking nut 27 may be screwed home to pre-
vent loosening, although of course the parts
may be removed by first loosening this lock
nut and then loosening the threaded re-
tainer bar by a suitable wrench or other in-
strument coöperating with its head 26 or
with any suitable part on the body of the
bar such as the nut 24 which may be formed
thereon. If desired the retainer bar 29 co-
operating with the nozzle member in one of
130

the outer wheel chambers may coöperate with a suitable retainer washer 31 which may have a portion fitting within the alined hole in the outer partition of the casing, the 5 threaded end of this retainer rod having a suitable head or socket, such as 32, to be engaged by a wrench in tightening the same so as to force the other end of this retainer rod into the seat 23 in the nozzle 10 member 10 to hold it in proper coöperation with the alined nozzle aperture 21. A suitable set nut 30 may be used on this retainer rod and a threaded plug 33 may be screwed by the head 34 into the threaded outer end 15 of the alined aperture so as to close the same. A similar form of retainer is shown in Figs. 1 and 3 for holding the high pressure nozzle members in position to coöperate with the high pressure wheel 5. Fig. 5 20 shows another arrangement in which the lock nut 38 is arranged on the outside of the threaded plug 37 which is screwed into the threaded hole in the outer partition of the casing, the square head 36 on the outer 25 end of the retainer rod 29 serving to operate it to hold the coöperating nozzle member in proper position and if desired a suitable cap 35 being screwed into place to cover the head and lock nut:

30 Fig. 6 shows another form of retainer device in which the retainer spider 22 is located on the other side of the partition 16 on which the connected nozzle member 10 is located so that both the retainer spider and 35 nozzle may coöperate with the same nozzle aperture 21. The retainer rod 39 in this instance extends through the nozzle aperture preferably adjacent the side thereof which is away from the turbine wheel and the 40 threaded ends of this retainer rod may be engaged by suitable nuts, such as 40, 41, to hold the supporting nozzle tube having the flange 28 and the connected nozzle member in proper position with respect to the turbine 45 wheel.

The nozzle member may, if desired, be formed integral with the supporting tube as by casting or otherwise and as indicated in Fig. 7 the nozzle member may be provided 50 with the passage 121 substantially in line with the alined nozzle aperture 21 so as to supply motive fluid to the initial injecting nozzle 48 of any desired form. For some purposes it is desirable to have a nozzle 55 valve to control the amount of fluid supplied to each injecting nozzle or to cut off all fluid supplied thereto and this may be conveniently effected by mounting a suitable nozzle valve 49 within the recess 50 in the 60 nozzle member and operating this valve by the connected stem 51 having a threaded portion 65 extending through the turbine casing and provided on its outer end with a suitable valve handle, such as 53. This 65 allows each injecting nozzle to be separately

closed so that, for instance, the alternate nozzles coöperating with each wheel may be shut off when desired and the amount of fluid admitted to each injecting nozzle can of course be suitably regulated.

70 The turbine wheel, such as 4, may be formed with suitable partitions 56 to form the annular series of lapping curved buckets 81 in the circumference of the wheel, each preferably having an admission side making the same angle with the wheel circumference. These bucket partitions 56 are preferably formed with beveled rear edges so as to direct the steam into the buckets to the best advantage, the discharge portions of 75 the bucket partitions being preferably beveled on their forward edges as indicated in dot and dash lines in Fig. 7. Also if desired suitable recesses, such as 59, may be formed in the inner side of each bucket adjacent the bucket bottoms so as to make the buckets of substantially uniform thickness at this point. The injecting steam is of course moving faster than the turbine wheel so that the steam tends to collect or bank 80 up against the forward flat sides of the buckets adjacent their bottoms in case the bucket bottoms are made with square sections. For this reason it is more desirable to form the curved bucket bottoms with suitable oblique recesses, such as 57, adjacent their rear sides so as to cause the streams of fluid passing through the buckets to spill or move back along these obliquely recessed bucket bottoms and equalize the 85 distribution of fluid at this point. The angle of the recesses in the curved bucket bottoms may be made sufficient to secure the substantially uniform distribution of the stream of steam or other motive fluid at this point, as is indicated diagrammatically by the substantially uniform steam layers 98 and so forth. The partitions forming the 90 annular series of lapping buckets may be curved or warped in any desired way so as to give the discharge side of a wheel bucket 95 a different angle, in the plane of the wheel's rotation, from the admission side of the bucket. By backwardly bending or warping the bucket sides the angular advance of the wheel during the time the fluid remains in the bucket may be compensated for and other disturbing forces of the wheel taken care of, as well as absorbing more energy 100 from the motive fluid which exerts a more continuous pressure against the backwardly warped bucket side which may with good results be substantially uniformly warped backward from its admission portion so as to discharge the fluid from the wheel bucket 105 at substantially the same angle as it is injected into the admission portion thereof. Such warped bucket sides are shown in Fig. 7, the admission portions of the buckets 56 being shown in section and the backwardly 110 warped sides being shown in section and the backwardly 115 warped sides being shown in section and the backwardly 120 warped sides being shown in section and the backwardly 125 warped sides being shown in section and the backwardly 130 warped sides being shown in section and the backwardly

warped discharge portions of the buckets being shown in dot and dash line to indicate that they are in front of the line of section which is taken substantially through the admission side of the buckets as will be seen from the section line 7—7 of Fig. 4 which shows the offset center portions 54 between the admission portions 56 and discharge portions 58 of the bucket sides or partitions.

10 As shown in Fig. 7 the injecting nozzles 48 of the nozzle members are preferably in line with the sides of the coöperating bucket so as to inject the motive fluid directly into the same and in order to utilize the motive fluid by passing it several times through the wheel buckets before it is discharged into the chamber suitable forwardly advancing return passages may be formed in the nozzle member 10 so as to receive the motive fluid 15 from the discharge sides of the wheel buckets and return it to more advanced wheel buckets for another pass therethrough. Each of these advancing return passages preferably has its receiving and returning portions parallel in 20 order to make the motive fluid more effective and these return passages may be formed by providing suitable integral diaphragms, such as 86, 87 and 88 within the nozzle or return member 10. In order to equalize the 25 distribution of steam or other motive fluid in the advancing return passages each return passage may have its curved bottom obliquely recessed at its forward portion so as to promote the forward spilling or sliding 30 of the motive fluid at the bottom of the return passage and return to the wheel a substantially uniformly distributed stream of motive fluid. The angle of the oblique recess 47 in the bottom of the return passage 35 may be arranged so as to secure the proper equalizing action and as indicated in Figs. 7 and 8 a suitable distributing flange, such as 46, may if desired also be formed on the rearward wall or diaphragm so as to 40 project into the return passage adjacent its curved bottom and exert the desired distributing action on the fluid stream at this point while leaving the receiving portion of the return passage and its returning portion entirely 45 free from any obstruction. The distributing flange 46 may as indicated have a slightly curved cross-section and may project about half way into the return passage 83, although if desired the distributing flange 50 may be substantially parallel to the recessed curved bottom 47 of the return passage as in the case of the distributing flange 45 projecting somewhat farther into the return passage 84. The distributing flange 44 projecting 55 into the return passage 85 makes a suitable angle with its recessed bottom so as to be at substantially right angles to the diaphragm 87 on which the distributing flange is mounted, it being of course understood that any of these forms of distribut-

ing flanges may be used in all of the return passages or the return passages may be formed without distributing flanges.

The course of the motive fluid can be understood by reference to Figs. 7 and 8, the steam or other fluid being injected through the injecting nozzle 48 so as to enter the bucket parallel to the bucket sides and form a fluid stream, such as 98 therein. The dot and dash lines 101, 102 show somewhat diagrammatically the course of this stream of fluid through the return passage 83 leaving the backwardly warped discharge portion of the bucket until it is again returned to the succeeding bucket in a parallel direction substantially parallel to the sides of this bucket. The motive fluid passing through this bucket forms a fluid stream, such as 99, whose cross-section may be substantially equalized by the obliquely recessed bucket bottom, this fluid stream passing out of the backwardly warped discharge portion of the bucket and through the second return passage 84 as indicated by the dot and dash lines 103, 104 so as to be again returned in a parallel direction to the succeeding wheel bucket to form the fluid stream 100 therein. This fluid may as indicated be received into the return passage 85 and discharged therefrom in a parallel direction as indicated by the dot and dash lines 105, 106 so as to pass through the wheel buckets the desired number of times before it is allowed to discharge into the wheel chamber.

The nozzle members may be arranged around the wheel at the desired intervals and may be connected together so as to more rigidly hold them in alignment by forming suitable projecting portions or lugs of the proper length to coöperate with the succeeding nozzle member preferably adjacent its supporting tube as by having the connecting lug 62 on one nozzle member engage a suitable alining or connecting hole 63 in the next member, or if desired the connecting lugs may be seated in suitable recesses, such as 61, in supports 60 connected in any desired way to the partition or other portion of the turbine casing and preferably used adjacent the meeting edge or flanges 6 of the divided casing. The nozzle members may be spaced somewhat farther apart than shown in Fig. 7, as is diagrammatically indicated by the broken line at the forward portions of the nozzle members and the forward ends of the nozzle members may be relieved or recessed at the discharge side or portion of the turbine wheel so as to allow the discharge of fluid therefrom into the wheel casing at this point.

The turbine wheels may be conveniently formed of cast iron, bronze, steel or other desired material by the process described in the Hopson and Rearick Patent No. 1,008,478.

of November 14, 1911. By the use of specially shaped cores formed in corresponding core boxes the bucket partitions in the wheel may be given the desired backward warping and the turbine buckets may be formed with the bottom recesses and relieved portions as previously described. The rear edges of the bucket partitions may of course be beveled to some extent when originally 10 cast or may be subsequently beveled to the desired extent by obvious means.

Having described this invention in connection with a number of illustrative embodiments, forms, proportions, numbers of 15 parts, arrangements, materials and processes of manufacture, to the details of which disclosure the invention is not of course to be limited, what is claimed as new and what is desired to be secured is set forth in the appended claims.

I claim—

1. In elastic fluid turbines, a longitudinally divided casing provided with partitions forming wheel chambers, an annular 25 admission passage formed in said casing, the high pressure wheel chamber coöperating with said admission passage being of greater diameter than another wheel chamber, said casing having alined nozzle apertures formed 30 in said partitions and nozzle apertures in the high pressure wheel chamber beyond the body of said casing, a shaft carrying in said chambers bucketed turbine wheels having bucket sides backwardly warped from their 35 admission to their discharge portions, the wheel in said high pressure chamber being of greater diameter than another of said 40 wheels, a series of supporting nozzles coöperating with said nozzle apertures and having return members connected therewith and 45 formed with return passages having parallel receiving and returning portions coöperating with the buckets of said wheels, retainers to hold 50 said supporting nozzles in said nozzle apertures, said casing partitions being provided with cast dovetail recesses, packing 55 housings secured in said recesses, metallic packing coöperating with said shaft and mounted in said packing housings, said casing being formed with alined telltale 60 passages in the meeting edges of some of said partitions, packing interposed between the sections of said casing, a transverse telltale hole through said casing and packing to join 65 said telltale passages and a telltale valve connected to said hole to control the discharge of material from said telltale passages.

2. In elastic fluid turbines, a longitudinally divided casing provided with partitions forming wheel chambers, said casing having alined nozzle apertures formed in 60 said partitions, a shaft carrying in said chambers bucketed turbine wheels having 65 bucket sides backwardly warped from their

admission to their discharge portions, a series of supporting nozzles coöperating with said nozzle apertures and having return members connected therewith and formed with return passages having parallel receiving and returning portions coöperating with the buckets of said wheels, retainers to hold 70 said supporting nozzles in said nozzle apertures, said casing partitions being provided with cast dovetail recesses, packing housings secured in said recesses, metallic packing coöperating with said shaft and mounted in said packing housings, said casing being formed with alined telltale passages in the meeting edges of some of said partitions, packing interposed between the sections of said casing, a transverse telltale hole through 75 said casing and packing to join said telltale passages and a telltale valve connected to said hole to control the discharge of material from said telltale passage.

3. In elastic fluid turbines, a longitudinally divided casing provided with partitions forming wheel chambers, said casing having alined nozzle apertures formed in 80 said partitions, a shaft carrying in said chambers bucketed turbine wheels having bucket sides backwardly warped from their admission to their discharge portions, a series of supporting nozzles coöperating with 85 said nozzle apertures and having return members connected therewith and formed with return passages having parallel receiving and returning portions coöperating with the buckets of said wheels, retainers to hold 90 said supporting nozzles in said nozzle apertures, said casing partitions being provided with packing housings, metallic packing coöperating with said shaft and mounted in said packing housings, said casing being formed with alined telltale 95 passages in the meeting edges of some of said partitions.

4. In elastic fluid turbines, a casing provided with a wheel chamber, a turbine wheel in said chamber having a cast rim provided with integral inclined partitions forming the sides of an annular series of lapping curved buckets, said bucket sides being substantially uniformly warped backward from their admission portions to discharge the 100 fluid from said buckets substantially parallel to the receiving portions of said buckets, the curved bucket bottoms being obliquely recessed at their rearward portions to equalize the fluid streams passing therethrough, a series of nozzles and connected nozzle members each formed with a series of advancing return passages, each of said return passages having substantially parallel receiving and returning portions to receive and deliver 105 fluid to the wheel buckets at substantially the same angle, the curved bottoms of said return passages being obliquely recessed at their forward portions to equalize the fluid streams passing therethrough, there being 110

115

120

125

130

- curved distributing flanges projecting into said return passages adjacent the bottoms thereof.
5. In elastic fluid turbines, a casing provided with a wheel chamber, a turbine wheel in said chamber provided with inclined partitions forming the sides of an annular series of lapping curved buckets, said bucket sides being substantially uniformly warped 10 backward from their admission portions to discharge the fluid from said buckets substantially parallel to the receiving portions of said buckets, the curved bucket bottoms being obliquely recessed at their rearward portions to equalize the fluid streams passing therethrough, a series of nozzles and connected nozzle members each formed with a series of advancing return passages, each of said return passages having substantially 15 parallel receiving and returning portions, the curved bottoms of said return passages being obliquely recessed at their forward portions to equalize the fluid streams passing therethrough. 70
10. In elastic fluid turbines, a casing provided with a wheel chamber, a turbine wheel in said chamber provided with backwardly warped buckets, an annular series of lapping curved buckets, a nozzle and connected nozzle member formed with an advancing return passage, said return passage having substantially parallel receiving and returning portions to receive and deliver fluid to the wheel buckets at substantially the same angle. 75
15. In elastic fluid turbines, a casing provided with a wheel chamber, a turbine wheel in said chamber provided with an annular series of lapping curved buckets, a nozzle and connected nozzle member formed with an advancing return passage, said return passage having substantially parallel receiving and returning portions to receive and deliver fluid to the wheel buckets at substantially the same angle. 80
20. In elastic fluid turbines, a casing provided with a wheel chamber, a turbine wheel in said chamber provided with inclined partitions forming the sides of an annular series of lapping curved buckets, said bucket sides being warped backward from their admission portions the curved bucket bottoms being obliquely recessed at their rearward portions to equalize the fluid streams passing therethrough, a series of nozzles and 85 nozzle members each formed with a series of advancing return passages, each of said return passages having substantially parallel receiving and returning portions. 90
25. In elastic fluid turbines, a casing provided with a wheel chamber, a turbine wheel in said chamber provided with an annular series of lapping curved buckets, a nozzle and connected nozzle member formed with an advancing return passage, said return passage having substantially parallel receiving and returning portions to receive and deliver fluid to the wheel buckets at substantially the same angle, a part of said return passage being obliquely recessed at its forward portion to equalize the fluid streams passing therethrough. 95
30. In elastic fluid turbines, a casing provided with a wheel chamber, a turbine wheel in said chamber provided with an annular series of lapping curved buckets, a nozzle and connected nozzle member formed with an advancing return passage, said return passage having substantially parallel receiving and returning portions to receive and deliver fluid to the wheel buckets at substantially the same angle, the curved bottom of said return passage being obliquely recessed at its forward portion to equalize the fluid streams passing therethrough. 100
35. In elastic fluid turbines, a casing provided with a wheel chamber, a turbine wheel in said chamber provided with an annular series of lapping curved buckets, a nozzle and connected nozzle member formed with an advancing return passage, said return passage having substantially parallel receiving and returning portions to receive and deliver fluid to the wheel buckets at substantially the same angle, the curved bottom of said return passage being obliquely recessed at its forward portion to equalize the fluid streams passing therethrough. 105
40. In elastic fluid turbines, a casing provided with a wheel chamber, a turbine wheel in said chamber provided with inclined partitions forming the sides of an annular series of lapping curved buckets, said bucket sides being warped backward from their admission portions, a series of nozzles and nozzle members each formed with a series of advancing return passages, each of said return passages having substantially parallel receiving and returning portions. 110
45. In elastic fluid turbines, a casing provided with a wheel chamber, a turbine wheel in said chamber provided with inclined partitions forming the sides of an annular series of lapping curved buckets, said bucket sides being warped backward from their admission portions to discharge the fluid from said buckets substantially parallel to the receiving portions of said buckets, a nozzle and a connected nozzle member formed with an advancing return passage, said return passage having substantially parallel receiving and returning portions, the curved bottom of said return passage being obliquely recessed at its forward portion to equalize the fluid streams passing therethrough, there being a curved distributing flange project- 115
50. In elastic fluid turbines, a casing provided with a wheel chamber, a turbine wheel in said chamber provided with inclined partitions forming the sides of an annular series of lapping curved buckets, a series of nozzles and nozzle members each formed with a series of advancing return passages, each of said return passages having substantially parallel receiving and returning portions. 120
55. In elastic fluid turbines, a casing provided with a wheel chamber, a turbine wheel in said chamber provided with inclined partitions forming the sides of an annular series of lapping curved buckets, said bucket sides being warped backward from their admission portions to discharge the fluid from said buckets substantially parallel to the receiving portions of said buckets, a nozzle and a connected nozzle member formed with an advancing return passage, said return passage having substantially parallel receiving and returning portions, the curved bottom of said return passage being obliquely recessed at its forward portion to equalize the fluid streams passing therethrough, there being a curved distributing flange project- 125
60. In elastic fluid turbines, a casing provided with a wheel chamber, a turbine wheel in said chamber provided with inclined partitions forming the sides of an annular series of lapping curved buckets, said buckets being warped backward from their admission 130

- ing into said return passage adjacent the bottom thereof.
14. In elastic fluid turbines, a casing provided with a wheel chamber, a turbine wheel in said chamber provided with integral inclined partitions forming the sides of an annular series of lapping curved buckets in the wheel circumference, said bucket sides being warped backward from their admission portions, a nozzle and a connected nozzle member formed with an advancing return passage, said return passage having substantially parallel receiving and returning portions, there being a curved distributing flange projecting into said return passage adjacent the bottom thereof. 70
15. In elastic fluid turbines, a casing provided with a wheel chamber, a turbine wheel in said chamber provided with inclined partitions forming the sides of an annular series of lapping curved buckets in the wheel circumference, a nozzle and a nozzle member formed with an advancing return passage, said return passage having substantially parallel receiving and returning portions, there being a curved distributing flange projecting into said return passage adjacent the bottom thereof. 75
16. In elastic fluid turbines, a turbine wheel having an integral cast rim provided with inclined partitions forming the sides of an annular series of lapping curved buckets, said bucket sides being substantially uniformly warped backward from their admission portions to discharge the fluid from said buckets substantially parallel to the receiving portions of said buckets, the curved bucket bottoms being obliquely recessed at their rearward portions to equalize the fluid streams passing therethrough, a nozzle and return passage, having substantially parallel receiving and returning portions, the curved bottoms of said return passages being obliquely recessed to equalize the fluid streams passing therethrough. 80
17. In elastic fluid turbines, a turbine wheel having an integral rim provided with inclined partitions forming the sides of an annular series of lapping curved buckets, said bucket sides being warped backward from their admission portions, the curved bucket bottoms being obliquely recessed at their rearward portions to equalize the fluid streams passing therethrough, a nozzle and advancing return passage, having substantially parallel receiving and returning portions, the curved bottoms of said return passages being obliquely recessed at their forward portions to equalize the fluid streams passing therethrough. 85
18. In elastic fluid turbines, a turbine wheel having an integral cast rim provided with inclined partitions forming the sides of an annular series of lapping curved buckets, said bucket sides being warped, the curved bucket bottoms being obliquely recessed at their rearward portions to equalize the fluid streams passing therethrough, a nozzle and advancing return passage, having substantially parallel receiving and returning portions, the curved bottoms of said return passages being obliquely recessed at their forward portions to equalize the fluid streams passing therethrough. 90
19. In elastic fluid turbines, a turbine wheel having an integral rim provided with inclined partitions forming the sides of an annular series of lapping curved buckets, said bucket sides being warped, a nozzle and advancing return passage having substantially parallel receiving and returning portions. 95
20. In elastic fluid turbines, an integral cast turbine wheel provided with inclined partitions forming the sides of an annular series of lapping curved buckets, said bucket sides being warped backward from their admission portions to discharge the fluid from said buckets substantially parallel to the receiving portions of said buckets, the curved bucket bottoms being obliquely recessed at their rearward portions to equalize the fluid streams passing therethrough, a nozzle and return passage, having substantially parallel receiving and returning portions, the curved bottoms of said return passages being obliquely recessed to equalize the fluid streams passing therethrough. 100
21. In elastic fluid turbines, an integral cast turbine wheel provided with inclined partitions forming the sides of an annular series of lapping curved buckets, said bucket sides being warped backward from their admission portions, the curved bucket bottoms being obliquely recessed at their rearward portions to equalize the fluid streams passing therethrough, a nozzle and return passage having substantially parallel receiving and returning portions. 105
22. In elastic fluid turbines, an integral cast turbine wheel provided with inclined partitions forming the sides of an annular series of lapping curved buckets, said bucket sides being substantially uniformly warped backward from their admission portions, a nozzle and return passage having substantially parallel receiving and returning portions. 110
23. In elastic fluid turbines, an integral cast turbine wheel provided with inclined partitions forming the sides of an annular series of lapping curved buckets, said bucket sides being warped, a nozzle and return passage having substantially parallel receiving and returning portions. 115
24. The elastic fluid-turbine wheel having an integral cast web and rim provided with inclined partitions having beveled rear edges forming the sides of an annular series of 120

lapping curved buckets in the wheel circumference, said buckets being formed with recesses in their inner sides adjacent their bottoms to increase their bottom thickness, said 5 bucket sides being substantially uniformly warped backward from their admission portions to discharge the fluid from said buckets substantially parallel to the receiving portions of said buckets, the curved bucket bottoms being obliquely recessed at their 10 rearward portions to equalize the fluid streams passing therethrough.

25. The elastic fluid turbine wheel having an integral cast web and rim provided with 15 inclined partitions having beveled rear edges forming the sides of an annular series of lapping curved buckets in the wheel circumference, said bucket sides being substantially uniformly warped backward from 20 their admission portions, the curved bucket bottoms being obliquely recessed at their rearward portions to equalize the fluid streams passing therethrough.

26. The elastic fluid turbine wheel having an integral cast web and rim provided with inclined partitions having beveled rear edges forming the sides of an annular series of lapping curved buckets in the wheel circumference, said bucket sides being warped 25 backward from their admission portions.

27. The elastic fluid turbine wheel having an integral cast rim provided with inclined partitions forming the sides of an annular series of lapping curved buckets in the 35 wheel circumference, said bucket sides being warped backward from their admission portions.

28. The elastic fluid turbine wheel provided with integrally cast inclined partitions having beveled rear edges forming the 40 sides of an annular series of lapping curved buckets, said bucket sides being substantially uniformly warped backward from their admission portions to discharge the fluid from 45 said buckets substantially parallel to the receiving portions of said buckets, the curved bucket bottoms being obliquely recessed at their rearward portions to equalize the fluid streams passing therethrough.

50. 29. The elastic fluid turbine wheel provided with integrally cast inclined partitions forming the sides of an annular series of lapping curved buckets, said bucket sides being warped backward from their admission 55 portions, the curved bucket bottoms being recessed to equalize the fluid streams passing therethrough.

30. The elastic fluid turbine wheel provided with integrally cast inclined partitions forming the sides of an annular series of lapping curved buckets, said bucket sides being warped from their admission portions.

31. The elastic fluid turbine wheel provided with inclined partitions having beveled rear edges forming the sides of an an-

nular series of lapping curved buckets, said buckets being formed with recesses in their inner sides adjacent their bottoms to increase their bottom thickness, said bucket sides being substantially uniformly warped 70 backward from their admission portions to discharge the fluid from said buckets substantially parallel to the receiving portions of said buckets, the curved bucket bottoms being obliquely recessed at their rearward 75 portions to equalize the fluid streams passing therethrough.

32. The elastic fluid turbine wheel provided with inclined partitions forming the sides of an annular series of lapping curved 80 buckets, said bucket sides being warped backward from their admission portions, the curved bucket bottoms being obliquely recessed at their rearward portions to equalize the fluid streams passing therethrough.

33. The elastic fluid turbine wheel provided with inclined partitions forming the sides of an annular series of lapping curved buckets, said bucket sides being warped, the curved bucket bottoms being recessed to 85 equalize the fluid streams passing therethrough.

34. The elastic fluid turbine wheel provided with inclined partitions forming the sides of an annular series of lapping curved buckets, said bucket sides being warped 90 backward throughout part of their length.

35. The elastic fluid turbine wheel provided with integral inclined partitions forming the sides of an annular series of lapping 100 curved buckets, said bucket sides being warped.

36. The elastic fluid turbine wheel having an integral cast rim provided with inclined partitions forming the sides of an annular 105 series of lapping curved buckets, said bucket sides being substantially uniformly warped backward from their admission portions, the curved bucket bottoms being obliquely recessed at their rearward portions to equalize 110 the fluid streams passing therethrough.

37. The elastic fluid turbine wheel having an integral cast rim provided with inclined partitions forming the sides of an annular 115 series of lapping curved buckets, said bucket sides being warped backward from their admission portions.

38. The elastic fluid turbine wheel having a rim provided with inclined partitions forming the sides of an annular series of lapping curved buckets, said bucket sides being warped backward throughout part of 120 their length.

39. In elastic fluid turbines, a longitudinally divided casing provided with partitions forming wheel chambers, an annular admission passage formed in said casing, the high pressure wheel chamber co-operating with said admission passage being of greater diameter than another wheel cham- 125 130

ber, said casing having alined nozzle apertures formed in said partitions and nozzle apertures in the high pressure wheel chamber beyond the body of said casing, a shaft 5 carrying bucketed turbine wheels in said chambers, the wheel in said high pressure chamber being of greater diameter than another of said wheels and a series of nozzles coöperating with said nozzle apertures and 10 having return members connected therewith and formed with return passages coöperating with the buckets of said wheels.

40. In elastic fluid turbines, a longitudinally divided casing provided with partitions forming wheel chambers, an annular admission passage formed in said casing, the high pressure wheel chamber coöperating with said admission passage being of greater diameter than another wheel chamber, said 15 20 casing having alined nozzle apertures formed in said partitions and nozzle apertures in the high pressure wheel chamber beyond the body of said casing, a shaft carrying bucketed turbine wheels in said chambers, and a series of nozzles coöperating with said nozzle apertures.

41. In elastic fluid turbines, a longitudinally divided casing provided with partitions forming wheel chambers, said casing 30 being formed with alined telltale passages in the meeting edges of some of said partitions, packing interposed between the sections of said casing, a transverse telltale hole being formed through said casing and 35 packing to join said telltale passages and a telltale valve connected to said hole to control the discharge of material from said telltale passages.

42. In elastic fluid turbines, a longitudinally divided casing provided with partitions forming wheel chambers, said casing being formed with telltale passages in the meeting edges of some of said partitions, a transverse telltale hole being formed 45 through said casing to join said telltale passages.

43. In elastic fluid turbines, a longitudinally divided casing provided with partitions forming wheel chambers, said casing 50 being formed with telltale passages in the meeting edges of some of said partitions.

44. A longitudinally divided casing provided with partitions forming wheel chambers for elastic fluid turbines or the like, 55 said casing being formed with a telltale passage in the meeting edges of some of said partitions, and a telltale valve to control the discharge of material from said telltale passage.

60 45. A divided casing provided with partitions, said casing being formed with a telltale passage in the meeting edges of some of said partitions.

46. In elastic fluid turbines, a longitudinally 65 divided casing provided with partitions

forming wheel chambers and having alined nozzle apertures in said partitions, turbine wheels in said chambers, a series of supporting nozzles and connected nozzle members having interlocking connecting members and retainers to hold said nozzles in said nozzle apertures and comprising a threaded stem to engage each nozzle member and a coöperating relatively adjustable spider having alining lugs coöperating with an alined nozzle aperture in another of said partitions. 70 75

47. In elastic fluid turbines, a longitudinally divided casing provided with partitions forming wheel chambers and having alined nozzle apertures in said partitions, turbine wheels in said chambers, a series of supporting nozzles and connected nozzle members, retainers to hold said nozzles in said nozzle apertures and comprising a stem to engage each nozzle member and a coöperating relatively adjustable spider having alining lugs coöperating with an alined nozzle aperture in another of said partitions. 80 85

48. In elastic fluid turbines, a casing provided with partitions forming wheel chambers and having alined nozzle apertures in said partitions, turbine wheels in said chambers, a series of supporting nozzles and connected nozzle members, retainers to hold said nozzles in said nozzle apertures and comprising a stem and a coöperating relatively adjustable spider in another of said partitions. 90 95

49. In elastic fluid turbines, a longitudinally divided casing provided with partitions forming wheel chambers and having alined nozzle apertures in said partitions, turbine wheels in said chambers having interlocking connecting members, retainers to hold said nozzles in said nozzle apertures and comprising a stem to engage each nozzle member and a coöperating relatively adjustable spider having alining lugs coöperating with an alined nozzle aperture. 10 10

50. In elastic fluid turbines, a casing provided with partitions forming wheel chambers and having alined nozzle apertures in said partitions, turbine wheels in said chambers, a series of nozzles, retainers to hold said nozzles in said nozzle apertures and comprising a stem to engage each nozzle member and a coöperating relatively adjustable spider having alining lugs coöperating with an alined nozzle aperture. 11 11

51. In elastic fluid turbines, a casing provided with partitions forming wheel chambers and having alined nozzle apertures in said partitions, turbine wheels in said chambers, a series of nozzles, retainers to hold said nozzles in said nozzle apertures and comprising a stem to engage each nozzle member and a coöperating relatively adjustable member coöperating with an alined aperture. 12 12

52. In elastic fluid turbines, a casing provided with partitions forming a wheel chamber and having alined nozzle aper- 130

tures in said partitions, a turbine wheel in said chamber, a nozzle, a retainer to hold said nozzle in one of said nozzle apertures and comprising a stem to engage said nozzle member and a coöperating relatively adjustable member coöperating with an alined aperture.

53. In elastic fluid turbines, a casing provided with partitions forming a wheel chamber and having alined nozzle apertures in said partitions, a turbine wheel in said chamber, a nozzle, a retainer to hold said nozzle in one of said nozzle apertures and comprising a stem to engage said nozzle member and adapted to be engaged by an operating device inserted through an alined aperture from one end of said casing.

54. In elastic fluid turbines, a longitudinally divided casing there being partitions formed in the casing sections and having nozzle apertures in said partitions, a bucketed wheel and wheel shaft coöperating with said casing, a series of supporting nozzle members and connected nozzle tubes mounted in said nozzle apertures, a connecting member on each of said nozzle members loosely coöperating with a connecting socket in an adjacent nozzle member adjacent the supporting nozzle tube thereof to allow circumferential expansion and a support mounted adjacent the side of one of said casing sections to support the connecting member of the adjacent nozzle member.

55. In elastic fluid turbines, a longitudinally divided casing there being partitions formed in the casing sections and having nozzle apertures in said partitions, a bucketed wheel and wheel shaft coöperating with said casing, a series of supporting nozzle members and connected nozzle tubes mounted in said nozzle apertures, a connecting member on each of said nozzle members coöperating with a connecting socket in an adjacent nozzle member adjacent the supporting nozzle tube thereof and a support mounted adjacent the side of one of said casing sections to support the connecting member of the adjacent nozzle member.

56. In elastic fluid turbines, a longitudinally divided casing there being partitions formed in the casing sections and having nozzle apertures in said partitions, a bucketed wheel and wheel shaft coöperating with said casing, a series of supporting nozzle members and connected nozzle tubes mounted in said nozzle apertures, a connecting member on each of said nozzle members coöperating with a connecting socket in an adjacent nozzle member.

60 57. In elastic fluid turbines, a longitudinally divided casing formed with partitions there being nozzle apertures in said partitions, a bucketed wheel and wheel shaft coöperating with said casing, a series of nozzle members and connected nozzle tubes

mounted in said nozzle apertures, a connecting member on each of said nozzle members coöperating with a connecting member on an adjacent nozzle member adjacent the supporting nozzle tube thereof to hold said nozzle members in alinement while supported from said nozzle tubes.

58. In elastic fluid turbines, a casing formed with partitions there being nozzle apertures in said partitions, a bucketed wheel and wheel shaft coöperating with said casing, a series of nozzle members and connected nozzle tubes mounted in said nozzle apertures, a connecting member on each of said nozzle members coöperating with a connecting member on an adjacent nozzle member to hold said nozzle members in alinement while supported from said nozzle tubes.

59. In elastic fluid turbines, a casing formed with partitions, a bucketed wheel and wheel shaft coöperating with said casing, a series of nozzle members and connected nozzle tubes mounted in said casing, a connecting member on each of said nozzle members coöperating with a connecting member on an adjacent nozzle member to hold said nozzle members in alinement while supported from said nozzle tubes.

60. In elastic fluid turbines, a casing, a bucketed wheel and wheel shaft coöperating with said casing, a series of nozzle members and connected nozzle tubes mounted in said casing and a connecting member on each of said nozzle members coöperating with a connecting socket in an adjacent nozzle member.

61. In elastic fluid turbines, a casing, a bucketed wheel and wheel shaft coöperating with said casing, a series of nozzle members comprising return passages and connected nozzle tubes mounted in said casing and a connecting member on each of said nozzle members coöperating with a connecting socket in an adjacent nozzle member.

62. In elastic fluid turbines, a casing formed with partitions, a bucketed wheel and wheel shaft coöperating with said casing, a series of nozzle members comprising return passages and connected nozzle tubes mounted in said casing, a connecting member on each of said nozzle members coöperating with a connecting member on an adjacent nozzle member to hold said nozzle members in alinement while supported from said nozzle tubes.

63. In elastic fluid turbines, a casing, a bucketed wheel coöperating with said casing, a series of nozzle members and connected nozzle tubes mounted in said casing and means on one of said nozzle members and interlocking with an adjacent nozzle member to promote the alinement of said nozzle members.

64. In elastic fluid turbines, a casing, a bucketed wheel coöperating with said cas-

ing, a series of nozzle members each having adjacent one end a connected nozzle supported from said casing and means adjacent the other end of one of said nozzle members 5 and coöperating with another nozzle member to support such other end of said nozzle member.

65. In elastic fluid tubes a turbine wheel provided with inclined partitions forming 10 the sides of an annular series of lapping curved buckets in the circumferential portion of said wheel, said partitions having beveled rear edges at the admission portions of said buckets and having beveled front 15 edges at the discharge portions of said buckets, said bucket sides being substantially uniformly warped backward from their admission portions to have the discharge portion of each bucket at a different angle from its 20 admission portion and a nozzle member coöperating with said wheel and having a series of advancing return passages provided with warped sides.

66. In elastic fluid turbines, a turbine 25 wheel provided with inclined partitions forming the sides of an annular series of lapping curved buckets in said wheel, said partitions having beveled rear edges at the admission portions of said buckets and having 30 beveled front edges at the discharge portions of said buckets, said bucket sides being warped backward from their admission portions to have the discharge portions of each bucket at a different angle from its 35 admission portion, and a nozzle member coöperating with said wheel and having a series of advancing return passages provided with warped sides.

67. In elastic fluid turbines, a turbine 40 wheel provided with inclined partitions forming the sides of an annular series of lapping curved buckets in said wheel, said bucket sides being warped backward throughout part of their length to have the discharge 45 portion of each bucket at a different angle from its admission portion, and a nozzle member coöperating with said wheel and having a series of advancing return passages provided with warped sides.

68. In elastic fluid turbines, a turbine 50 wheel provided with inclined partitions forming the sides of an annular series of lapping curved buckets in said wheel, said bucket sides being warped to have the discharge 55 portion of each bucket at a different angle from its admission portion, and a nozzle member coöperating with said wheel and having a series of advancing return passages provided with warped sides, the edges of 60 said bucket partitions at the receiving and discharge portions of said wheel buckets and also the edges of the receiving and returning portions of said return passages all being parallel to one another.

69. The elastic fluid turbine wheel pro-

vided with inclined partitions forming the sides of an annular series of lapping curved buckets of said wheel, said partitions having beveled rear edges at the admission portions of said buckets and having beveled front edges at the discharge portions of said buckets, said bucket sides being warped backward from their admission portions to have the discharge portion of each bucket at a different angle from its admission portion. 70

70. The elastic fluid turbine wheel provided with inclined partitions forming the sides of an annular series of lapping curved buckets of said wheel, said bucket sides being warped backward throughout part of their length to have the discharge portion of each bucket at a different angle from its admission portion. 75

71. The elastic fluid turbine wheel provided with inclined partitions forming the sides of an annular series of lapping curved buckets, said partitions having beveled rear edges at the admission portions of said buckets and having beveled front edges at the discharge portions of said buckets, said bucket sides being bent backward from their admission portions to have the discharge portion of each bucket at a different angle from its admission portion. 80

72. The elastic fluid turbine wheel provided with inclined partitions forming the sides of an annular series of lapping curved buckets, said bucket sides being warped backward to have the discharge portion of each bucket at a different angle from its admission portion. 90

73. The elastic fluid turbine wheel provided with inclined partitions forming the sides of an annular series of lapping curved buckets in the circumferential portion of said wheel, said bucket sides being substantially uniformly warped backward from their admission portions to have the discharge portion of each bucket at a different angle from its admission portion, the edges of said partitions being substantially parallel at the receiving and discharge portions of said wheel buckets. 100

74. The elastic fluid turbine wheel provided with inclined partitions forming the sides of an annular series of lapping curved buckets in the circumferential portion of said wheel, said bucket sides being warped backward to have the discharge portion of each bucket at a different angle from its admission portion, the edges of said partitions being substantially parallel at the receiving and discharge portions of said wheel buckets. 110

75. The elastic fluid turbine wheel provided with inclined partitions forming the sides of an annular series of lapping curved buckets in the circumferential portion of said wheel, said bucket sides being bent backward from their admission portions to 120

130

have the discharge portion of each bucket at a different angle from its admission portion, the curved bucket bottoms being recessed to equalize the streams of fluid passing therethrough.

76. The elastic fluid turbine wheel provided with inclined partitions forming the sides of an annular series of lapsing curved

buckets, the curved bucket bottoms being recessed to equalize the streams of fluid passing therethrough.
